UNITED STATES PATENT OFFICE

2,434,002

FRONT END ELEVATOR FOR TRACTORS

Stanley S. Moore, Stockton, Calif.

Application August 20, 1945, Serial No. 611,635

1 Claim. (Cl. 187—11)

1

This invention is directed to, and it is an object to provide, an improved front end elevator for tractors.

An additional object of the invention is to provide a front end elevator which is arranged for easy mounting on, or removal from, a tractor; said elevator including a power winch which is mounted as a unitary part of, and removable with, said elevator from the tractor.

Another object of this invention is to provide a front end elevator which includes a vertically extensible elevator frame assembly whereby the implement has a relatively low normal height but a relatively great height when extended; extension of said frame assembly being accomplished by the power winch above mentioned.

A further object of the invention is to provide a novel cable system between said power winch and the several parts of the extensible elevator frame assembly, whereby the latter may be extended forcefully and yet smoothly.

A further object of the invention is to provide a simple and inexpensive device, and yet one which will be exceedingly effective for the purpose for which it is designed.

These objects are accomplished by means of such structure and relative arrangement of parts as will fully appear by a perusal of the following specification and claim.

In the drawings similar characters of reference indicate corresponding parts in the several views:

Figure 1 is a front elevation of the device as mounted on a tractor.

Figure 2 is a side elevation of the main frame alone, showing the manner of its attachment to a tractor.

Figure 3 is a fragmentary plan view of the device.

Figure 4 is a cross section on line 4—4 of Fig. 1.

Figure 5 is a cross section on line 5—5 of Fig. 4.

Referring now more particularly to the characters of reference on the drawings, the improved front end elevator for tractors comprises an upstanding main frame, indicated generally at 1, and which main frame comprises a pair of transversely spaced vertical frame beams 2 rigidly connected at the top by a cross beam 3 and adjacent the bottom by cross bracing 4. This main frame 1 is adapted to be removably supported from a tractor 5, ahead of the radiator 6 thereof, in the following manner:

2

A pair of horizontal, transversely spaced connection beams 7 are removably secured to opposite sides of the tractor frame by means of bolts 8; the connection beams 7 projecting forwardly to a termination some distance ahead of the radiator 6, and at which point of termination said beams are secured to attachment ears 9 on corresponding ones of the frame beams 2, as at 10, the ears 9 being disposed adjacent but short of the lower end of said main frame 1. A diagonal brace 11 is connected between each of the frame beams 2 a substantial distance above the ears 9, and an intermediate point on the corresponding connection beam 7. Mounted as above defined the main frame 1 is rigidly vertically supported in forwardly facing relation in advance of the tractor.

On the outside thereof the frame beams 2 each support a plurality of vertically spaced rollers 12 which guidingly cooperate with a vertically movable elevator frame, indicated generally at 13. The elevator frame 13 comprises a pair of transversely spaced, vertically disposed I-beams 14 secured together adjacent top and bottom, and at the front clear of the laterally facing channels of said I-beams, by cross members indicated at 15 and 16. The innermost channels 17 of the I-beams 14 have the guide rollers 12 engaged therein, whereby the elevator frame 13 is freely movable vertically in guided relation.

An elevator carriage 18 extends horizontally across the front of the assembly of main frame 1 and elevator frame 13, and includes, at the sides, 35 rearward extensions 19, on each of which a pair of vertically spaced rollers 20 are mounted; said rollers projecting inwardly and riding in the laterally outwardly facing channels 21 of the I-beams 14 of the elevator frame 13.

By reason of the above described arrangement, the elevator carriage 18 is vertically movable relative to the elevator frame 13, while the latter is vertically movable relative to the main frame 1, 45 whereby to provide a vertically extensible elevator assembly.

The elevator carriage 18 is formed, at the front, with a front plate 22 including top and bottom flanges 23 projecting forwardly from corresponding edges of said front plate. To the front plate 22 there is removably attached the load engaging members, here shown as transversely spaced, forwardly projecting lift-fork elements 24, which include attachment legs 25 removably secured in 55 abutting relation against the front plate 22 be-

tween the flanges 23. For certain types of work, the lift-fork elements 24 may be removed and other types of work engaging means substituted, as for example a scoop (not shown).

The elevator frame assembly is actuated, from its normally lowered or contracted position, to an elevated or extended position by the following means:

A power winch, indicated generally at 26, is fixedly supported in the main frame 1 intermediate the top and bottom thereof, and between the frame beams 2, by means such as a bracket 27. This power winch 26 includes a drive pulley 28 driven from the crank shaft 29 of the tractor by means of an endless belt 30.

A cable 31 is connected to the cable drum 32 of the power winch and extends upwardly over a direction-changing sheave 33 on the front of the main frame 1 adjacent the top and one side of the latter. From the sheave 33 the cable extends downwardly about a sheave 34 on the front of the elevator frame 13 at the bottom and to the corresponding side thereof. Thence the cable runs upwardly to the top of the elevator frame and thence over another sheave 35 on the top thereof and on the same side. From the sheave 35 the cable extends downwardly and about a transverse axis sheave 36 on the corresponding end of the elevator carriage 18. From the sheave 36 the cable extends upwardly to the back of the main frame at the top, passing over an adjacent sheave 37 and thence extending across the back of said main frame and about a top and back sheave 38 on the other side of said main frame. From the sheave 38 the cable extends down the right side of the elevator frame assembly and is thence reeved about sheaves 39, 40, and 41, corresponding respectively in position to the sheaves 36, 35, and 34, but on the opposite side of the elevator frame assembly. From the sheave 41 the cable extends upwardly and is dead-ended on the main frame, as at 42.

The power winch 26 is controlled by the operator of the tractor by control means not here shown; said winch being normally braked and not operative. However, upon brake release and operation of the winch 26 the cable 31 winds onto the cable drum 32, which causes a shortening of the cable system on both sides of the elevator frame assembly, resulting in smooth but forceful lifting of the elevator frame 13 and the elevator carriage 18. The amount of extension of the frame assembly is of course under the control of the operator, whereby he can effectively regulate the height to which the load is raised by the elevator carriage 18.

When it is desired to remove the front end elevator from the tractor it is only necessary to detach the bolts 8, whereupon the connection beams 7, together with the remainder of the device, may be readily detached from said tractor. As the power winch 26 is mounted as a unitary part of the device, and as said winch is belt-driven, it is only necessary that the endless belt 30 be removed to separate the drive means for the winch 65 from the tractor crank shaft 29.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful, and upon which Letters Patent are desired:

A front end elevator for tractors including a rigid, substantially rectangular main frame, means for attaching said main frame in a substantially vertical position to a tractor frame, a cable drum winch mounted within the main frame with its drum axis extending transversely of the frame, detachable means to connect the winch drum with a power take-off on the tractor, an elevator frame mounted for guided vertical movement relative to the main frame, an elevator carriage mounted for guided vertical movement relative to the elevator frame, a sheave on the main frame disposed ahead of the front plane thereof and adjacent one side of the frame with its axis parallel with the drum axis, a sheave disposed at each side of both the upper and lower ends of the elevator frame and with their axes parallel with the drum axis, a sheave at each end of the elevator carriage, the axis of said carriage sheaves lying transversely of the drum axis, a sheave at the back of the main frame at each end thereof, the axes of said latter named sheaves lying parallel to the drum axis, a cable on the drum, such cable being reeved through the sheave on the front side of the main frame, thence about the lower sheave on the corresponding side of the elevator frame, thence about the upper sheave on said side of the elevator frame, thence about the carriage sheave on the corresponding end of the carriage, thence over the sheave on the back frame adjacent said side, thence passing back of the main frame to the opposite side thereof and thence about the back sheave on the main frame on that side, hence about the carriage sheave on that side, hence about the top sheave on the elevator frame on that side, hence about the lower elevator sheave on that side, the end of said cable being then secured to the main frame adjacent the upper end thereof.

STANLEY S. MOORE.
